UNITED STATES PATENT OFFICE.

HUBERT M. FREEMAN, OF EAST PITTSBURGH, PENNSYLVANIA, ASSIGNOR TO WESTINGHOUSE ELECTRIC & MANUFACTURING COMPANY, A CORPORATION OF PENNSYLVANIA.

RADIO VACUUM TUBE.

Application filed January 8, 1924. Serial No. 684,981.

This invention relates to vacuum tube devices.

It is an object of this invention to produce a non-microphonic tube.

5 More specifically stated, it is an object of the invention to diminish the vibration of the standards which carry the electrodes. In many devices, such vibrations result from mechanical jar of the tube.

10 It is an object of my invention ancillary to the object just mentioned, to avoid right angle bends in certain of the standards. Heretofore, these bends have been deemed necessary in order to accommodate the supporting devices which project laterally from these standards. This object of the invention has been accomplished by rearranging the several standards in the press.

20 Another object of my invention is to provide a system of standards for supporting the electrodes which shall be straight or nearly so.

If all of the standards were entirely straight, the parts extending at right angles from some standards would contact with 25 others. This condition is avoided in the present invention by very slightly bending certain of the standards.

It is an object of this invention to reduce the bending of the standards to a minimum.

30 An object of this invention, incidental to the object just mentioned, is to provide a pair of standards which shall engage along two elements of the cylinder constituting the plate, these elements being in a plane at an 35 oblique angle to the plane of the press.

It is a further object of this invention to so arrange the leads from the standards in their new positions that the external contact pins shall have the same relative positions as 40 in the vacuum tubes heretofore used.

In vacuum tubes of this type, as heretofore manufactured, the standard for supporting the grid, and the standard for supporting the upper end of the filament are each provided 45 with a right-angle offset close to the press. These offsets are nearly at right angles to the plane of the press, which causes the whole assembly to be bulky and give the tube a crowded appearance. In the form embodying my invention, this appearance is avoided 50 by arranging all of the standards nearly in one plane.

The standards for the grid and for the upper end of the filament each have supporting devices extending laterally from them 55

toward the center of the tube. In the tubes of this type heretofore used, the right angle bends in these standards were necessary to accommodate the supporting devices. Space for these devices is obtained by means of my 60 invention without bending these standards, by locating the standards, which carry laterally extending devices, at the sides of the press, and the other standards between them. In the prior art, bent standards have been 65 placed next to the central standard.

This change in the relative positions of the standards requires, in order to accommodate the new form of tube to the standardized four terminal pins, that two of the leads from the 70 standards cross each other. Accordingly, the lead from the top of the filament is made to pass the lead from the plate in the hollow part of the press.

In this invention, the standards which support the plate are the only standards that are 75 bent. The bend required is very much less than the right-angle bends required in the tubes formerly used. Tubes of the former style have the plate-supporting standards at 80 the sides of the press. The distance between them at the press is, therefore, greater than the diameter of the plate. Consequently the standards in this former style are bent slightly to bring them to the plate. The bends 85 used in the plate-supporting standards, in this invention, are no greater than the bends in these standards in the tubes heretofore used.

The right-angle bends near the press, the 90 bending of both plate and other standards, the fact that these bends are in different planes, and the fact that some of the offsets are large, are all features of the tubes of older style which are avoided by the present 95 invention resulting in a very great increase in convenience in manufacture.

Other objects of the invention and details of the construction will be apparent from the following description and the accompanying 100 drawings in which:

Figure 1 is a top plan view of the electrodes and press,

Fig. 2 is a side view of the same with a diagrammatic indication of the connections 105 to the contact pins, and

Fig. 3 is a view taken at right angles to that of Fig. 2.

The press 1 is of the usual form, including a hollow part 2 and a flattened portion which 110

secures the standards in place. The central standard 3 is attached to the lower end of the filament 4 by the usual connector. The upper end of the filament is secured to the top of a standard 6 by the usual connector and the spring 5.

The standard 6 occupies the right-hand position in the press, as shown in Figs. 1 and 2. The standard 7, at the left-hand side 10 of the press, supports the grid 8 by means of the usual U-shape device, including two arms 9 welded to the standard and extending laterally therefrom.

The plate 11 is supported by two standards 12 and 13 each of which is bent slightly where it emerges from the press and is bent a second time, as shown at 14 and 15 in Fig. 3, to make the upper portions of the standards parallel. These parallel portions, as best shown in 20 Fig. 1, lie in a plane making an angle of about 45 degrees with the plane of the press. This gives ample room for the lower arm 9 to go to the grid without danger of its contacting with the plate standard 13.

Each of the standards, except 13, pass 25 through the flattened part of the press into the tubular part thereof, and constitute leads, which go to the exterior contact pins, by which the tube is connected to the apparatus with which it is used. In order that this tube may be used with the same apparatus as tubes of this type heretofore in use, the several electrodes must be connected to contact pins located in the same relative positions as in the old devices. In order to accomplish this 30 result, the leads from standards 6 and 12 pass each other at an angle, as shown at 17 in Fig. 2. It is, of course, understood that these crossing leads are not in the same plane and that, therefore, there is no likelihood of

contact between them. The pin 18, which is connected to the plate, is of larger size than the three other contact pins in order to prevent incorrect insertion of the tube in the apparatus.

45

Various modifications of the details of the invention will be apparent to those skilled in the art, and I do not, therefore, intend that the single specific form illustrated shall be interpreted as a limitation. No limitations 50 except those necessitated by the prior art or indicated in the accompanying claims are intended.

50

I claim as my invention:

1. In a vacuum tube device, a press, a cylindrical plate, two standards mounted in said press and secured to said plate along elements of the cylinder, the plane of said elements being at an oblique angle to the plane of said press.

55

2. In a vacuum tube device, a press, a cylindrical plate, two standards mounted in said press and secured to said plate along elements of the cylinder, the plane of said elements being at an oblique angle to the plane of said press and each of said standards having two bends between the plate and the press.

60

3. In a vacuum tube device, a press, a cylindrical plate, two standards mounted in said press and secured to said plate along elements of the cylinder, the plane of said elements being at an oblique angle to the plane of said press and each of said standards having two bends between the plate and the press, each of said bends being less than 45 degrees.

65

In testimony whereof, I have hereunto subscribed my name this 17th day of December, 1923.

HUBERT M. FREEMAN.
